DESIGN FOR A RUG.

No. 38,795.

Specification for Design.

Patented Sept. 10, 1907.

Application filed August 6, 1907. Serial No. 387,365. Term of patent 3½ years.

To all whom it may concern:

Be it known that I, ADOLPH PETZOLD, a citizen of the United States, residing in the city of Philadelphia, State of Pennsylvania, have invented a certain new original Design for a Rug, of which the following is a specification, reference being had to the accompanying drawings, forming a part thereof.

My design relates to and is intended for the surface ornamentation of a woven rug.

In said drawings is shown a plan view of one half thereof, the other half of the design (not shown) being a duplicate or repeat thereof.

I claim:—

The ornamental design for a rug, as shown.
